UNITED STATES PATENT OFFICE.

CLIFFORD T. SONDELEY, OF NEWBERRY, SOUTH CAROLINA.

MACHINE FOR REBABBITTING CONNECTING RODS.

Application filed April 24, 1924. Serial No. 708,784.

To all whom it may concern:

Be it known that I, CLIFFORD T. SONDELEY, a citizen of the United States, residing at Newberry, in the county of Newberry and State of South Carolina, have invented certain new and useful Improvements in Machines for Rebabbitting Connecting Rods, of which the following is a specification, reference being had to the accompanying drawings.

This invention relates to machines for casting, and particularly to mechanism for casting Babbitt metal within the bearings of connecting rods.

One of the objects of the invention is to provide a machine of this character, which is very simple, which may be readily operated, and which is expeditious and effective in its work.

A further object is to provide a construction of this character wherein means are provided for clamping a connecting rod in place against movement, there being a core which fits within the eye of the connecting rod, and providing a Babbitt metal pot normally containing melted Babbitt metal, the die, as it may be termed, with the connecting rod and the pot being relatively movable so as to bring the parts toward each other and into proper engagement, means being provided then operating to force the Babbitt metal into the die and between the core and the wall of the connecting rod.

A still further object is to provide a detailed construction whereby the die may be readily removed so that a new die may be put in place for casting the bearing of a larger or smaller connecting rod and whereby a proper adjustment may be secured between the die and the connecting rod and between the spout or nose of the Babbitt metal pot and the die.

Another object is to provide means for properly centering the connecting rod including pins adapted to pass through the bolt hole openings for the bearing at this end of the connecting rod.

Other objects will appear in the course of the following description.

My invention is illustrated in the accompanying drawings, wherein:—

Figure 1 is a longitudinal sectional view through a mechanism constructed in accordance with my invention;

Figure 2 is a horizontal sectional view on the line 2—2 of Figure 1;

Figure 3 is a sectional view on the same lines as Figure 1 but showing the carriage moved forward and the die brought into engagement with the Babbitt metal pot;

Figure 4 is a fragmentary section on the line 4—4 of Figure 3;

Figure 5 is a front elevation of the carriage, the frame within which the carriage moves being in section;

Figure 6 is a front view of the die plate;

Figure 7 is an enlarged vertical section of a portion of the die plate, the core support and the connecting rod showing the manner in which the space between the connecting rod and the core is filled with Babbitt metal;

Figure 8 is a vertical sectional view of a slightly modified form of apparatus designed particularly for casting a half bearing;

Figure 9 is a fragmentary sectional view on the line 9—9 of Figure 8;

Figure 10 is a rear elevation of the die plate with the core, the guide rods being in section;

Figure 11 is a side elevation of the die plate core;

Referring to the drawings, the mechanism is mounted within a frame consisting of the longitudinally extending members 10 and the transverse members 11. This frame may be mounted upon columns or otherwise supported at a convenient height above the floor. Supported on this frame and extending longitudinally thereof are four parallel rods 12 which pass through the end members 11 of the frame and are held in place by nuts 13. Also supported upon the frame at one end thereof by the transverse supports 14 is the melting pot, which is designated generally 15, and which is adapted to contain Babbitt metal. The construction of this melting pot will be later stated.

Sliding upon the rods 12 is a supporting plate forming one part of a carriage, the plate being designated 16, and carrying the sleeves or collars 17 which slidably embrace the rods 12. Mounted upon this plate 16 by the bolts 18 is a yoke 19 which supports a transverse shaft 20 having a handle 21 at one end. Mounted upon the forward face of the yoke 19 is one section 22

of the die. This section 22 is recessed, as at 23, and counter-recessed, as at 24. This is held in place upon the face of the yoke 19 by means of a longitudinally movable rod 25, the forward end of which is reduced in diameter where it passes through the section 22 and is then formed with a head 26. The rear end of this rod passes through the plate 16 and, as illustrated in Figure 3, is screw-threaded at 27 and is engaged by an elongated nut 28 carrying thereon the hand wheel 29. The hub 28 is held from longitudinal movement by means of a plate 30 held in spaced relation but parallel to the plate 16 by means of the bolts 31 and the spacers 32. By turning this hand wheel in one direction or the other, the die section 22 may be either drawn up tightly against the face of the yoke 19 or moved outward from the face of the yoke 19. At the same time the die section 22 will move with the plate 16, which in turn is movable upon the rods 12, as before stated.

Coacting with the fixed die section 22 is a movable die section comprising a centrally disposed plate 33 and an outer plate 34, the outer plate being recessed or rabbeted at its margin and the central plate 33 being complementarily rabbeted so that the two plates, when placed together, are flush with each other. The plate 33 is held in engagement with the outer frame or plate 34 by means of the screws 35.

Attached to the outer plate 34 are longitudinally extending rods 36 which extend rearward from this plate 34, pass through the yoke 19 and through the plate 16. Two of these rods, which I have designated 37, have rack teeth upon their under faces and are engaged by the gear wheels 38, which in turn are mounted upon the shaft 20. By turning this shaft 20 in one direction or the other, the die plate 33 may be drawn into coactive engagement with the die member 22, as shown in Figure 3, or shifted out into the position shown in Figures 1 and 2. This die plate 33 is formed with a centrally projecting hub 39, the base of which is surrounded by an annular groove 40, and it is to be noted at this point that this groove 40 has a diameter equal to the diameter of the counterbore 24, while the hub 39 has a diameter equal to the internal diameter of the recess 23 so that when the parts are drawn over to the position shown in Figure 3, this member 39 will enter the socket 23 and fit closely therein. The hub 39 under these circumstances forms the inner wall of an annular recess formed by the counterbore 24 and the inner wall, of course, of the annular recess 40. The rods 36 are reduced at their forward ends to pass through the bores in the annular plate 34 and are screw-threaded for the reception of nuts. This permits the

member 34 to be readily removed in case it is desired from these rods.

For the purpose of moving the carriage 16 toward or from the Babbitt pot 15, I mount upon each bracket 41 the transverse shaft 42 having thereon the projecting handle 43. Extending downward from the shaft 42 adjacent its extremities are the arms 44. These arms are connected to links 45, which in turn extend upward and are pivotally connected to bifurcated cleats 46 having screw-threaded shanks which pass through the plate 16 and are held in place thereon by nuts, as shown in Figure 2. It will be obvious now that by pulling down upon the lever or handle 43, the carriage composed of the plates 16, the yoke 19, the die section 22 and the die section 33 will move forward toward the Babbitt pot, and upon a movement of the handle or lever 43 back to the position shown in Figure 1, all of these parts will be retracted.

For the purpose of holding a connecting rod such as shown in Figure 4 in position where the eye of the connecting rod which engages with the usual crank shaft may be babbitted, I mount upon the plate 16 and above the section 22 a guide 47. This guide is arcuate in transverse section and projects outward beyond the extremity of the member 22 and, as illustrated in Figure 4, is provided with the two vertical openings or bores 48. Oscillatably mounted upon the plate 16 above this guide 47 is a cam 49 which is pivoted eccentrically upon a bolt or other pivot member 50, this cam being formed with the cam track 51 and having projecting therefrom the handle 52 whereby the cam may be oscillated in one direction or the other (see Figure 5).

Operating within this cam track is a pin 53 which projects from an angular member 54, this angular member, as shown in Figure 4, being provided with the downwardly projecting pins 56. These pins are adapted to extend through the bores or openings for the bolts normally used to connect the two sections *a* and *b* of the connecting rod bearing. This connecting rod, which is designated *A*, will be formed all in one piece, that is the section *a* will not be separated from the section *b*, or in other words will not be cut through as yet and thus the pins 56 will hold what may be termed the head end of the connecting rod firmly in place when the pins 56 are passed through these openings which are cast in the head of the connecting rod for the passage of the usual bolts. By operating the lever 52, as shown in Figure 3, the pins 56 may be drawn upward out of these openings, and by turning the lever in the other direction the cam will force these pins down into the head of the connecting rod. As will be seen, the cam track 51 is so eccentric that a considerable range of

movement can be secured for this member 54 which carries the pin 56 and thus connecting rods having heads of larger or smaller sizes may be readily engaged.

- 5 The melting pot 15, as shown in Figure 2, has a central web 57 extending inward from the adjacent wall of the melting pot, this web terminating in an enlargement 58 wherein is formed the vertically extending 10 chamber 59. This chamber has an opening 60 in one wall thereof which opens into the melting pot, while the opposite wall of the chamber below the opening 60 is formed with a relatively small discharge passage 61 15 which, as shown in Figure 3, extends upward and then outward through a nozzle 64 formed in the wall of the melting pot. This nozzle 64 is tapered at its extremity so that it fits into the mouth of a sprue opening 65 20 which extends into the annular recess 40, as shown in Figure 3.

Operating within the cylindrical chamber 59 is a plunger 66 by which the molten metal is forced out through the passage 61 into 25 and through the sprue opening, this plunger 66 at its upper end being toothed, as at 67, and being engaged by a pinion 68 mounted upon a shaft 69 carried by a bracket 70, this shaft 69 being provided with a handle 30 71. The bracket is apertured for the passage of the rack bar 72, this rack bar being separate from the plunger 66 and being engaged therewith by means of a union or collar 73. The lower end of the chamber 35 59 is formed with an opening closed by a plug 74, and below this chamber there is provided means 75, designated in dotted lines in Figure 3, whereby the Babbitt pot may be heated.

40 The Babbitt metal pot is rigidly bolted to the frame bars of the machine but the carriage is movable along the rails 12, and in order to support the forward end of the yoke 19 and prevent any possible chance of 45 this yoke sagging downwardly, I provide a brace 76 projecting from the yoke at one or both ends, this brace carrying upon it a roller 77 which rolls along the adjacent rail 12.

50 In order to hold the lower end of the connecting rod A, I form in the plate 16 the slot 78, and passing through this slot is a pin 79, the rear end of which is reduced in thickness and screw-threaded, as at 80, for 55 the reception of a nut 81. A washer 82 bears against the wall of the slot and the nut bears against this washer. This pin 79 is adapted to pass through the eye c at the lower end of the connecting rod, as shown in Figure 3, and the pin is supported in its adjusted 60 position against any downward movement by forming the pin 79 with a rectangular enlargement or shank 83, as it may be called, which is engaged by a screw 84 having 65 swiveled engagement with this enlargement

83 and passing through a screw-threaded fixed nut 85 mounted upon the plate 16 by means of the screw-threaded shank and nut 86. The slot 78 permits this pin 79 to be adjusted toward or from the center of the 70 die section 22 and the square end of the shank portion 83 holds the bearing or eye c at the lower end of the connecting rod in the proper vertical plane. The pin 79 is adjusted vertically within the slot by screwing up or down upon the adjusting screw 84, and it is obvious that by taking off the nut 81 other pins may be substituted for any one pin, thus adapting the device to be used with connecting rods having bearings of 80 different sizes. The same is true with regard to the die sections 22 and 33, which may be changed and varied so as to suit connecting rods having different sized bearings. 85

In the operation of this mechanism, the babbitt is, of course, supposed to be in a molten condition, and before the connecting rod is put in place the piston 66 is raised, as illustrated in Figure 1, so that the chamber 59 has communication with the interior of the pot and metal will flow from the pot into this chamber 59. The passage 61, it will be seen, is at a height somewhat above that of the opening 60 and this passage is so constructed that the metal will not flow out through the passage until this plunger 66 is depressed, when the metal will be forced out through this passage 61 and spurted into the bearing. If it be desired to properly babbitt a connecting rod of the form shown in Figure 4, which connecting rod be it understood has not yet had its bearing divided into two sections, the connecting rod is disposed with its lower bearing upon the pin 79 and is then disposed with its upper bearing against the end of the die section 22. The cam 49 is then turned to cause the depression of the pins 48 through the apertures in the member 47 and into the apertures for the passage of the bolts through the upper bearing of the connecting rod, as shown in Figure 4. This locks the connecting rod in the position shown in Figure 3 so that one end of the upper bearing forms 100 the wall for the recess 24. The handle or lever 43 is then turned from the position shown in Figure 1 to that shown in Figure 3, which shifts the carriage longitudinally 105 along the rails 12 and forces the bearing into the position shown in Figure 3 against the die plate 33 and the hub of this die plate through the bearing. At this time a stop 87 which is adjustably engaged with a support 88 (see Figure 3) limits the downward 110 movement of the lever 43 and the parts are, therefore, projected to the full extend of the links 45. This will bring the plate 33 with its sprue opening 65 into engagement with the nozzle 64, but if it does not do this and 115 120 125 130

there is need of a further adjustment, which is, of course, requisite to accommodate the various thicknesses of connecting rods, this adjustment can be secured by turning the hand wheel 29, which rotates the nut 28 and forces the rod 25 outward, thus shifting the mold sections bodily forward. This fine adjustment secured by the nut 28 and the screw-threads 27 may also be used for the purpose of adjusting the connecting rod A into such position that it will receive the pins 48 and thus this fine adjustment permits the machine to compensate for variations in the size of the connecting rod.

After the connecting rod has been brought into proper position, the handle 52 is operated to cause the pins 48 to be forced downward into the head of the connecting rod, as shown in Figure 4, and thus hold the connecting rod from any turning movement. The plunger 66 is then depressed by means of the handle 71 and the molten liquid forced out into the space between the hub 29 and the yoke of the connecting rod, as shown in Figure 4. When this plunger 66 is retracted, it will be noticed from Figure 1 that the plunger moves up above the opening 60 and permits passage of molten liquid through this opening into the chamber 59, but when the plunger moves downward it cuts off this flow of liquid. The collar 73, it will be seen, acts as a stop preventing the too great depression of the plunger, and this collar 73 is so disposed relative to the length of the plunger, or the plunger 66 is of such length, that when the collar 63 is depressed so as to strike the upper end of the melting pot, just enough Babbitt metal will have been discharged to form the ordinary bearing.

In Figures 8 to 11, I show another form of my invention which is particularly adapted for casting a half bearing and in which the adjustment of the dies toward and from each other and toward and from the pot of Babbitt metal is secured by other means than that described. This mechanism is also mounted in a rectangular frame, as previously described, and as the construction of the Babbitt pot is exactly the same as in the apparatus shown in Figure 3, the same reference numerals have been used for this part of the mechanism. A carriage is provided as of practically the same construction as heretofore described, this carriage consisting of a back plate 16^a sliding upon guide bars 12^a. A yoke 19^a is mounted upon the plate 16^a and through which the guide rods pass. The die section 22^a is mounted upon the yoke plate 19 by means of a plurality of bolts or screws 88, which in turn hold a socket member 89 to the yoke plate.

Attached to the member 19^a disposed within the socket and extending rearward therefrom is a rack bar 90 which is en-

gaged by a pinion 91 mounted upon a shaft 92, this shaft in turn being operated by means of the relatively large hand wheel 93. By this means the carriage may be shifted forward or backward and brought toward or from the Babbitt pot. The front die formed of the parts 33^a and 34^a is carried upon guide rods 94, and disposed on each side of the carriage are the guide and operating rods 95 which are toothed, as at 96, for engagement by the pinion 97 mounted upon a shaft 98.

These parts are practically the same as the parts previously described for drawing the front die toward the rear die and illustrated in Figure 2. The die 23^a is slightly differently constructed, as shown in Figures 9 and 10, from the die 33. The hub 39^a of this die carries laterally projecting wings 99 which are apertured for the passage of bolts 100, which bolts are adapted to pass through the half bearing *a'* formed upon the connecting rod *a* (see Figure 9). These wings 99, of course, form dams and extend into slots in the hub 39^a. When the molten metal is forced through the nozzle and through the aperture in the plate 33^a, it fills all the space between the core, wings and the inner face of the bearing *b'*, as shown in Figure 9. The lower portion of the bearing may be made at a different time with this apparatus, this lower section of the bearing, which would correspond to the section *a* in Figure 4, being disposed in place of the section *b*, as shown in Figures 8 and 9.

The operation of the mechanism is precisely the same as it was before. The two sections of the die are separated by operating the shaft 98 and then the connecting rod is inserted in place and the sections drawn up together to the position shown in Figure 8. When this has been done the wheel 93 is operated to cause the carriage to travel forward until the nozzle 64^a enters the opening in the plate 33^a and the piston 66^a is depressed by the mechanism heretofore described and the molten metal driven into the bearing. The carriage is then retracted, the two mold sections separated, and the yoke removed.

It will be seen that when the yoke is disposed upon the wings 99, bolts 100 are passed through these wings and through the bearing, as shown in Figure 9, to thus hold the bearing rigidly in place. I have illustrated the plate 33 and the plate 33^a as being formed with only one sprue opening through which metal is disposed into the interior of the yoke, but obviously two or more sprue openings might be used for this purpose.

The reason for using the construction shown in Figures 8 and 9 for the purpose of casting the Babbitt metal for half bearings is that these bearings are usually large

and it is impossible to cast the whole bearing at one time, as there is liability of the metal chilling before the interior of the connecting rod bearing has been filled with Babbitt metal. The casting of a bearing in two sections at different times, as disclosed in Figures 8 and 9, is of particular advantage where there is a very large connecting rod which takes a bearing requiring several 10 times the quantity of Babbitt metal that some of the smaller rods take, thus creating a danger of the babbitt becoming chilled before it is thoroughly distributed over the rod. Of course, it would be possible to 15 heat the connecting rod so as to prevent any chilling of the metal, but this is not expedient and would require additional operating expense.

While I have illustrated a form of my invention which I have found to be very successful in actual operation, I do not wish to be limited thereto as it is obvious that the device might be embodied in other forms than that shown and that the mechanism 25 is, therefore, susceptible to considerable variation over what I have illustrated.

I claim:—

1. A machine for casting Babbitt metal within bearing yokes, the machine including 30 a Babbitt metal pot having a discharge nozzle, a carriage movable toward or from the nozzle, a pair of dies mounted upon the carriage and adapted to clamp the article to which the Babbitt metal is to be applied 35 between the dies, means for shifting said dies toward or away from each other, means for shifting the carriage as a whole and the dies toward the melting pot along a line passing through the axis of the discharge nozzle, one of said dies being provided with a sprue opening adapted to communicate with the interior of the yoke and in which sprue opening the nozzle is adapted to extend, and means for forcing the molten 45 metal out through said nozzle.
  2. Means for casting Babbitt metal in bearing yokes including a melting pot having a discharge nozzle, a pair of coacting dies adapted to be brought together to clamp 50 the article to which the Babbitt metal is to be applied between them, one of said dies being provided with a sprue opening, means for shifting both of said dies toward the Babbitt melting pot along a line passing 55 through the axis of the discharge nozzle, to therefore carry the nozzle into the sprue opening, and means for forcing the molten metal out through said discharge opening and into the space between the dies.
  3. Mechanism for casting Babbitt metal in bearing yokes including a melting pot having a discharge nozzle, guides extending from the melting pot, a carriage movable upon the guides, a pair of coacting dies between which the article to be provided with
- Babbitt metal is mounted, means for causing the dies to move away from or shift toward each other to thereby clamp the article, means for shifting both of said dies bodily upon said rods toward the melting pot, the outer die having a sprue opening, with which the nozzle is adapted to coincide, and means for forcing molten metal from said melting pot through said discharge opening. 70
4. Means for casting Babbitt metal in connecting rod bearing yokes comprising a melting pot having a discharge nozzle, guides extending toward the melting pot, a carriage traveling upon said guides, means on the carriage for supporting a pair of coacting dies between which the article to be babbitted is adapted to be placed, one of said guides having a sprue opening in its outer face in line with the nozzle and having an inwardly projecting hub upon its inner face forming a core, means for manually shifting said dies toward or from each other, means for locking the connecting rod with a yoke end between said dies, means for shifting the carriage bodily toward the melting pot to bring the sprue opening in the die into coincidence with the nozzle of the melting pot, and means for forcing the metal out of the melting pot through said discharge opening. 80
5. Means for casting Babbitt metal within the bearing yokes of connecting rods including a melting pot having a chamber in communication with the body of the melting pot, there being a discharge passage leading from said chamber to one face of the melting pot, a piston operating in said chamber, guides extending from the chamber, a carriage movable upon said guides toward and from the melting pot, coacting dies operatively mounted upon the carriage, one of said dies having a sprue opening with which the discharge opening of the chamber is adapted to coincide, the opposite face of the die having a projecting hub, the other die having a recess to receive the hub and the dies having annular recesses surrounding the hub and said first named recess respectively, manually operable means for shifting the first named die toward or from the second named die, manually operable means for shifting the carriage toward or from the melting pot, and means for locking a connecting rod in place with its yoke between said dies, said means being shiftable to release the connecting rod. 90
6. Means for casting Babbitt metal within the yokes of connecting rods including a melting pot having a chamber in communication with the body of the melting pot, there being a discharge passage leading from said chamber to one face of the melting pot, a piston operating in said chamber, guides extending from the chamber, a car- 100
- 105
- 110
- 115
- 120
- 125
- 130

riage movable upon said guides toward and from the melting pot, coacting dies operatively mounted upon the carriage, one of said dies having a sprue opening with which the discharge opening of the chamber is adapted to coincide, the opposite face of the die having a projecting hub, the other die having a recess to receive the hub and the dies having annular recesses surrounding the hub and said first named recess respectively, manually operable means for shifting the first named die toward or from the second named die, manually operable means for shifting the carriage toward or from the melting pot, and means for locking a connecting rod in place with its yoke between said dies, said means comprising a member mounted on the carriage to engage that end of the connecting rod remote from that end into which the Babbitt metal is to be cast, said means being shiftable to release the connecting rod.

7. Means for casting Babbitt metal within the yokes of connecting rods including a melting pot having a chamber in communication with the body of the melting pot, there being a discharge passage leading from said chamber to one face of the melting pot, a piston operating in said chamber, guides extending from the chamber, a carriage movable upon said guides toward and from the melting pot, coacting dies operatively mounted upon the carriage, one of said dies having a sprue opening with which the discharge opening of the chamber is adapted to coincide, the opposite face of the die having a projecting hub, the other die having a recess to receive the hub, the dies having annular recesses surrounding the hub and said first named recess respectively, manually operable means for shifting the first named die toward or from the second named die, manually operable means for shifting the carriage toward or from the melting pot, means for locking a connecting rod in place with its yoke between said dies, said means comprising a pin adapted to engage in the yoke at that end of the connecting rod remote from that end which is to receive the Babbitt metal, the pin being adjustable toward or from the axes of the dies, and means mounted upon the carriage adjacent the dies for locking the connecting rod against rotary movement.

8. Means for casting Babbitt metal within the yokes of connecting rods including a melting pot having a chamber in communication with the body of the melting pot, there being a discharge passage leading from said chamber to one face of the melting pot, a piston operating in said chamber, guides extending from the chamber, a carriage movable upon said guides toward and from the melting pot, coacting dies operatively mounted upon the carriage, one of

said dies having a sprue opening with which the discharge opening of the chamber is adapted to coincide, the opposite face of the die having a projecting hub, the other die having a recess to receive the hub and the dies having annular recesses surrounding the hub and said first named recess respectively, manually operable means for shifting the first named die toward or from the second named die, manually operable means for shifting the carriage toward or from the melting pot, means for locking a connecting rod in place with its yoke between said dies, said means comprising a pin shiftable into or out of a bolt hole in the connecting rod, and manually operable means for shifting said pin.

9. Means for casting Babbitt metal within the yokes of connecting rods including a melting pot having a chamber in communication with the body of the melting pot, there being a discharge passage leading from said chamber to one face of the melting pot, a piston operating in said chamber, guides extending from the chamber, a carriage movable upon said guides toward and from the melting pot, coacting dies operatively mounted upon the carriage, one of said dies having a sprue opening with which the discharge opening of the chamber is adapted to coincide, the opposite face of the die having a projecting hub, the other die having a recess to receive the hub and the dies having annular recesses surrounding the hub and said first named recess respectively, manually operable means for shifting the first named die toward or from the second named die, manually operable means for shifting the carriage toward or from the melting pot, means for locking a connecting rod in place with its yoke between said dies, said means comprising a pin shiftable into or out of a bolt hole in the connecting rod, and a cam mounted upon the carriage and operatively engaging said pin, the cam when oscillated acting to retract or project the pin.

10. In a mechanism for casting Babbitt metal within the yokes of connecting rods including a melting pot and having a nozzle, a carriage movable toward or from the melting pot and having coacting dies between which the yoke to be babbitted is to be placed and clamped, means for shifting said dies toward or from each other, one of said dies having a sprue opening adapted to coincide with the discharge nozzle of the melting pot, and means for shifting said carriage toward or from the melting pot including a rotatable shaft having a lever and toggle links, one of which is pivotally connected to the carriage and to the other link and the last named link being operatively connected to said shaft.

11. A mechanism for casting Babbitt

- metal in the yokes of connecting rods including a melting pot having a discharge passage and a nozzle, a pair of coacting dies adapted to receive and support between them the yoke of a connecting rod, means for shifting said dies toward or from each other, means for shifting both dies simultaneously toward or from the melting pot and bring the sprue opening in one of said dies into coincidence with the discharge opening of the melting pot, means for bodily shifting the dies comprising a rod having operative engagement with the dies, a rotatable nut having a handle and having screw-threaded engagement with the rod, and means for holding the nut from movement.
12. In a mechanism of the character described, a melting pot having an outlet passage and a discharge nozzle, guides, a pair of dies mounted upon said guides for independent movement toward or from each other and bodily movement toward or from the melting pot, the die adjacent the melting pot being provided with a sprue opening adapted to coincide with the nozzle of the melting pot, means for bodily shifting said dies toward or from the melting pot, means for independently shifting one of said dies toward or from the other die comprising rack bars carried by the movable die, a transverse shaft, and pinions mounted upon the transverse shaft and engaging said rack bars.
13. A mechanism of the character described comprising a supporting frame, a melting pot mounted thereon and having a discharge passage, a discharge nozzle projecting therefrom, means coacting with the melting pot whereby a certain charge of molten metal may be forced out through said passage and nozzle, guides extending longitudinally from the melting pot, a carriage mounted upon said guides and movable toward or from the melting pot, means for shifting the carriage toward or from the melting pot, a pair of coacting dies mounted upon said carriage, one of said dies being movable toward or from the other die, said last named die having a sprue opening coinciding with the nozzle of the melting pot, the two dies being adapted to clamp the yoke of a connecting rod between them, means for locking the bearing in place between said dies from any rotary movement, and manually operable means for shifting the dies longitudinally relative to the carriage.
14. A mechanism of the character described including a supporting frame, a melting pot mounted thereon, the melting pot including a discharge chamber, a plunger operating therein, manually operable means for reciprocating the plunger, the melting pot having a discharge passage leading from said chamber and a discharge
- nozzle into which the passage opens, guide rods extending from the melting pot, a carriage slidable from the guide rods, means for shifting the carriage toward or from the melting pot, dies operatively supported upon the carriage, one of said dies being fixed and the other die being movable toward or from the first die, the last named die being provided with a sprue opening adapted to coincide with the discharge nozzle of the melting pot and the dies being adapted to clamp a connecting rod between them, means for locking the connecting rod in place including a latching member adapted to engage the end of the connecting rod remote from the yoke disposed between the dies, means for locking that end of the yoke which is disposed between the dies comprising a member having a pair of pins adapted to extend into the bolt holes of the connecting rod, and a cam mounted upon the carriage and engageable with said member, said cam acting to shift the pins into or out of engagement with the connecting rod.
15. In a mechanism of the character described, opposed dies, one of which is formed with a central recess and a counterbore, the other of said dies having a hub adapted to be received in said recess and having an annular groove at the base of the hub and in alignment with the counterbore, the last named die being provided with an aperture constituting a sprue opening and extending through the die and into said groove.
16. In a mechanism of the character described, opposed dies, one of which is formed with a central recess and a counterbore, the other of said dies having a hub adapted to be received in said recess and having an annular groove at the base of the hub and in alignment with the counterbore, the last named die being formed of a central section and a marginal section, the last named section being detachably engaged with the central section and the central section being formed with a sprue opening extending from the annular groove to the outer face of the central section.
17. In a mechanism of the character described, a pair of coacting dies adapted to clamp one yoke of a connecting rod between them, one of said dies being formed with a core insertible through the yoke and the other being formed with a recess to receive the core, one of said dies having a sprue opening extending into the space between the core and the yoke, a member upon which one of said dies is mounted, means for locking the connecting rod in place from movement around the core comprising a latch having a shoulder, the latch being adapted to be inserted through the yoke of the connecting rod remote from the yoke being abutted, said latch having a shank and the

supporting member being provided with a slot through which the shank passes, and means for adjusting said latch comprising a screw mounted upon the supporting member and engaging the latch and having swiveled engagement with the latch.

18. In a mechanism of the character described, a pair of coacting dies adapted to clamp one yoke of a connecting rod between them, one of said dies being formed with a core insertible through the yoke and the other being formed with a recess to receive the core, one of said dies having a sprue opening extending into the space between the core and the bearing, a member upon which one of said dies is mounted, means for locking the connecting rod in place from movement around the core comprising a latch having a shoulder, the latch being adapted to be inserted through the yoke of the connecting rod remote from the yoke being babbitted, said latch having a shank and the supporting member being provided with a slot through which the shank passes, means for adjusting said latch comprising a screw mounted upon the supporting member and engaging the latch and having swiveled engagement with the latch, means for holding the opposite end of the connecting rod comprising an arcuate plate projecting from said member and over the head of the connecting rod and having a pair of perforations, pins operating through said perforations and adapted to engage in the bolt holes of the connecting rod head, and manually operable means for withdrawing or projecting said pins.
19. A machine for casting Babbitt metal within the bearings of a connecting rod comprising a clamp for the bearing portion of the rod including opposed dies between which the bearing portion of the connecting rod is adapted to be clamped, one of said dies having a core adapted to pass through the bearing portion of a connecting rod con-

centrically thereto and the other die being formed with a recess within which said core is received, and means for causing the discharge of molten Babbitt metal into the space defined by the dies and the bearing.

20. A machine for casting Babbitt metal within the split bearing of a connecting rod comprising a clamp for the bearing portion of the connecting rod including dies between which the bearing portion of the connecting rod is clamped, means for locking the two halves of the split bearing from relative movement, and means for causing the discharge of molten Babbitt metal into the space defined by the dies and the bearing.

21. A machine for casting Babbitt metal within the split bearing of a connecting rod comprising a clamp for the bearing portion of the connecting rod formed of two dies between which the bearing is clamped, a locking member having pins movable into position to carry the pins through the usual bolt apertures of the split bearing thereby locking the two halves against relative movement, and means for causing the discharge of molten Babbitt metal into the space defined by the dies and the bearing.

22. A machine for casting Babbitt metal within the bearings of a connecting rod comprising a clamp for the bearing, including dies within which the bearing portion of the connecting rod is clamped, a melting pot for the Babbitt metal having a discharge opening, means for causing the relative movement of the dies and melting pot toward or from each other on a line parallel to the axis of the discharge opening and into or out of conjunction, and means for causing the discharge of molten Babbitt metal from the melting pot into a space defined by said dies and the bearing when the dies are in conjunction with the melting pot.

In testimony whereof I hereunto affix my signature.

CLIFFORD T. SONDELEY.
